UNITED STATES PATENT OFFICE

155,799

DESIGN FOR A DRAFTING TABLE OR SIMILAR ARTICLE

Louis Gearhart, Manhattan Beach, Calif.

Application July 12, 1948, Serial No. 147,501

Term of patent 3½ years

(Cl. D33—14)

To all whom it may concern:

Be it known that I, Louis Gearhart, a citizen of the United States, residing at Manhattan Beach, in the county of Los Angeles and State of California, have invented a new, original, and ornamental Design for a Drafting Table or Similar Article, of which the following is a specification, reference being had to the accompanying drawing, forming a part thereof.

Fig. 1 is a perspective view of a drafting table or similar article showing my new design;

Fig. 2 is a side elevational view thereof;

Fig. 3 is a front elevational view.

I claim:

The ornamental design for a drafting table or similar article, substantially as shown.

LOUIS GEARHART.
